UNITED STATES PATENT OFFICE.

DANIEL BELCHER, OF WEBSTER GROVES, MISSOURI, ASSIGNOR TO BEMIS BRO. BAG COMPANY, OF ST. LOUIS, MISSOURI, A CORPORATION OF MISSOURI.

SHEET ACCUMULATOR.

Application filed May 9, 1921. Serial No. 467,848.

To all whom it may concern:

Be it known that I, DANIEL BELCHER, a citizen of the United States of America, a resident of Webster Groves, in the county 5 of St. Louis, State of Missouri, have invented certain new and useful Improvements in Sheet Accumulators, of which the following is a full, clear, and exact description, reference being had to the accompanying drawings, forming a part of this specification.

This invention relates to improvements in sheet-accumulators having sheet-holders adapted to receive collections of sheets. The 15 sheet material transmitted to the holders may be folded and in the form of bags, although it is to be understood that other forms of sheet material could be fed to and held by the sheet-holders.

20 One object of the invention is to provide an accumulator equipped with means for supporting and counting the sheets passing from a feeding device. More specifically stated, an object is to produce an apparatus 25 of this kind adapted to receive and count the bags passing from a bag-turning machine.

Prior to this invention, bags have been transmitted one at at time from a bag-turning machine, and after passing from the machine they have been picked up by an operator and counted while they are manually handled and arranged in piles. This handling of individual bags requires considerable 35 time and labor, and the counting is not always correct, so it has been customary to check the counting, either by weighing the piles of bags or by recounting the individual bags.

40 According to the present invention, the bags may be automatically counted and collected in piles as they pass from a bag-turning machine. This eliminates the labor ordinarily involved in handling and counting the individual bags, and it insures absolute accuracy in the counting of the bags.

With the foregoing and other objects in view, the invention comprises the novel construction, combination and arrangement of 50 parts hereinafter more specifically described and illustrated in the accompanying drawings wherein is shown the preferred embodiment of the invention. However, it is to be understood that the invention comprehends changes, variations and modifications

which come within the scope of the claims hereunto appended.

Briefly stated, the mechanism I have shown to illustrate one form of the invention includes a bag-turning device having a reciprocating plunger whereby the bags are turned, and an accumulator having a series of bag-holders, or sheet-holders, adapted to receive the bags passing from the bag-turning device. The accumulator moves step by step to successively locate the bag-holders in the path of the bag-turning plunger, each bag-holder being in the form of a gripper adapted to receive margins of a collection of bags. After a predetermined number of bags have been delivered to a bag-holder, all of the bag-holders are shifted to displace the collection of bags from the path of the bag-turning plunger while an empty bag-holder is positioned to receive the next collection of bags. The counting of the bags is determined by the transmission of motion from the bag-turning plunger and through the bags themselves, so if the plunger is idly acutated without feeding a bag to the bag-holder, there will be no effective operation of the counting mechanism. The motion of the counting mechanism is thus derived from the plunger which feeds the bags to the bag-holders, but this counting mechanism is not acutated unless a bag is delivered to a bag-holder.

Fig. I is a side elevation of a bag-turning machine equipped with an accumulator embodying the features of this invention.

Fig. II is an enlarged side elevation, partly in section, showing a portion of the accumulator to which the bags are delivered from the bag-turning mechanism.

Fig. III is a rear elevation of the machine shown in Fig. I.

Fig. IV is a detail view illustrating the means for opening the bag-holders in the accumulator.

Fig. V is a fragmentary view showing certain parts of the means for shifting the bag-holding arms in the bag-turning machine.

Fig. VI is a top or plan view of the machine shown in Figs. I and II, the accumulator being shown in section.

Fig. VII is a detail view of the means for controlling the counting mechanism of the accumulator.

Fig. VIII is a section taken approxi-

mately on the line VIII—VIII, Fig. VII, and showing a disk and ratchet wheel which do not appear in Fig. VII.

Fig. IX is a fragmentary view of a part 5 of the mechanism through which motion is transmitted to the bag-turning plunger.

Fig. X is an enlarged fragmentary top view of the bag-turning plunger and certain elements associated therewith.

10 Fig. XI is a side elevation of the parts shown in Fig. X, and also showing a part of the accumulator and the bag-holding arms which do not appear in Fig. X.

15 Fig. XII is a view similar to Fig. XI illustrating the parts in the positions they occupy when a bag is delivered to the accumulator.

20 Fig. XIII is an enlarged detail view showing the ratchet device whereby a step by step motion is imparted to the accumulator.

Fig. XIV is a side elevation of the parts at the upper portion of Fig. XIII, and also showing a part of the means for unlocking the accumulator.

25 Fig. XV is a vertical section showing the ratchet devices forming part of the counting mechanism.

Fig. XVI is a detail view of one of the ratchet devices shown in Fig. XV.

30 Fig. XVII is a side elevation of the ratchet device shown in Fig. XVI.

Fig. XVIII is an enlarged top or plan view showing a portion of the bag-turning plunger and also showing the arms which 35 hold the bag while it is acted upon by the plunger.

Fig. XIX is a section taken approximately on the line XIX—XIX, Fig. XVIII.

40 Fig. XX is a transverse section through the bag-holding arms, showing a bag on said arms, a portion of the bag being broken away to show the bag-turning plunger which reciprocates between the upper and lower arms.

45 The bag-turning mechanism includes a reciprocating plunger A and arms 1 and 2 whereby the bag is held while it is acted upon by the plunger. These arms (Figs. I, VI, XI, XVIII, XIX and XX) are supported by a carrier B slidably mounted on a horizontal rod 3, said carrier having a depending lug 4 (Figs. X and XIX) extending into a horizontal groove which lies parallel with the guide rod 3. The carrier B is thus guided in a straight, horizontal line and it can be reciprocated to locate the bag-holding arms 1 and 2 at the path of the bag-turning plunger A.

55 The bag-holding arms 2 are rigidly secured to the carrier B by means of screws 5, which are shown most clearly in Fig. XIX. Each arm 1 (Figs. XVIII and XIX) is secured by means of screws 6 to an operating arm 7, and each of said operating arms is pivoted to the carrier by means of a screw

8. The two operating arms 7 are parallel with each other and they are connected together through the medium of a spacer block 9 (Figs. XVIII and XIX) having a roll 10 which lies in a groove 11 formed in a stationary cam 12. When the carrier B is reciprocated along the guide rod 3, the roll 10 (Figs. XVIII and XIX) travels in the cam 12 with the result of moving the pivoted arms 1 toward and away from the arms 2, each arm 1 being pivoted at 8 and provided with an operating arm 7 to which the roll 10 is secured.

When the carrier B occupies the position shown by full lines in Figs. VI and XVIII, 80 the outer ends of the bag-receiving arms 1 lie adjacent to the arms 2, and a bag can then be very easily slipped onto said arms.

In Fig. VI I have shown a table 13 adapted to support the bags to be turned. When the machine is in service, the operator removes the top bag from a pile of bags on the table 13, and slips the bag onto the arms 1 and 2, while said arms are located in their bag-receiving positions entirely beyond the path 90 of the bag-turning plunger A. Thereafter the carrier B is actuated to shift these bag-receiving arms from the positions shown by full lines in Fig. XVIII to the positions

shown by dotted lines, and during this operation the roll 10 travels in the cam 12 for the purpose of moving the arm 1 away from the arm 2, and when said arms occupy the positions shown by dotted lines, the arm 1 is parallel with the arm 2. The bag-turning plunger A then moves to the left from the position shown by Fig. XVIII and it

engages the closed end of the bag with the result of turning the bag on the outer ends 95 of the arms 1 and 2. Figs. XIX and XX show that there are two upper arms designated 1 and 2 and two lower arms designated by the same characters. The bag-turning plunger A is in the form of a wide blade

100 which travels between the upper and lower arms while it engages the closed end of the bag X. The bag is thus turned, or reversed, while it is drawn around the outer ends of the arms 1 and 2, said outer ends being located adjacent to the plunger A in Figs. XI and XVIII. During the bag-turning operation, the bag is stripped from the arms 1 and 2, and the plunger A eventually forces the closed end of the bag into the accumulator, as will be hereafter described.

110 The cam 12 (Fig. XVIII) is normally stationary, although it is adjustably secured through the medium of a pivot 14 and a clamping screw 15.

115 The bag-turning plunger A is supported by a reciprocating carriage C slidably mounted on horizontal guide rods 16 which lie at a right angle to the guide rod 3. The carriage C includes tubular members surrounding the respective guide rods 16, and

120

125

130

a web 17 connecting said tubular members, as shown most clearly by Figs. XI and XII. The bag-turning plunger A is rigidly secured to a lug 18 which extends from the 5 web 17. It will now be understood that the carriage C, including its web 17 and lug 18, may be reciprocated along the guide rod 16, and that the plunger A will travel with this carriage.

10 The means for reciprocating the carriage C includes a long lever 19 (Figs. I, VI, XI and XII) and a link 20 connecting said lever to the carriage C. The lever 19 is pivotally supported at 21, as shown by Figs. I and VI. This lever is actuated through the medium of a crank 22 fixed to a shaft 23 (Figs. I and IX) and a link whereby motion is transmitted from the crank 22 to said lever 19. This link includes a rod 24 (Fig. IX) 15 and connecting devices 25 and 26 adjustably mounted on said rod, the rod being threaded to receive nuts between which the connecting devices are secured. The connecting device 25 is secured to the crank 22 through the medium of a pivot 27, and the connecting device 26 is attached to the lever 19 through the medium of a pivot 28. The shaft 23 is rotated continuously through the medium of a large gear wheel 29 (Figs. I and VI), 20 which is fixed to said shaft, a pinion 30 meshing with said gear wheel, said pinion being fixed to a shaft 31 provided with an operating pulley 32. The pulley 32 may be driven continuously with the result of transmitting motion through the mechanism just described and thereby imparting a reciprocating motion to the bag-turning plunger A.

I will now describe the means for reciprocating the carrier B to which the bag-holding arms 1 and 2 are secured. 33 designates a long operating lever (Figs. I, III and XIX) in the form of a bell crank pivotally supported by a pin 34 (Fig. III) and having a slot 35 at its upper end for the reception of a pin 36 on the reciprocating carrier B. A tension spring 37 is connected at its upper end to the short arm of the lever 33, as shown by Figs. I and III, the lower end of said spring being secured to a stationary 35 part of the machine frame. This spring 37 cooperates with the lever 33 to move the carrier B in one direction. The means for moving the carrier B in the opposite direction includes a cam 38 (Figs. I, V and VI) 40 on a rotary shaft 39, a lever 40 pivotally supported at 41 (Fig. V), said lever having a roll which engages the cam 38, and a link connecting the lever 40 to the long lever 33. This connecting link includes a rod 42 provided at its ends with connecting devices 43 (Figs. III and V) which are pivoted to the levers 33 and 40, respectively. The shaft 39 is rotated continuously, as will be hereafter described, and the cam 38 is secured to this 45 shaft for the purpose of actuating the lever

40, whereby motion is transmitted through the rod 42 and connecting devices 43 to the long operating lever 33, for the purpose of actuating the carrier B to which the bag-receiving arms 1 and 2 are secured. The 70 cam 38 serves as means for moving the lever 33 and carrier B in one direction, and these elements are restored through the medium of the spring 37 (Figs. I and III).

The means for rotating the cam shaft 39 75 comprises a bevel gear 44 fixed to said shaft 39 (Figs. I and VI) and a bevel gear 45 meshing with the gear 44, said gear 45 being secured to the rotary shaft 23.

It will now be understood that the bag-receiving arms 1 and 2 are secured to the reciprocating carrier B, and that the bag-turning plunger A is secured to a reciprocating carriage which travels in a line at a right angle to the path of the carrier B. The arms 1 and 2 are shifted from their bag-receiving positions shown by full lines in Figs. VI and XVIII, to their bag-turning positions shown by dotted lines in Fig. XVIII and by full lines in Figs. X and XX. 80 The bag-turning plunger A is shifted from the position shown by Figs. X and XI to the position shown by Fig. XII for the purpose of turning the bag X and delivering it to an accumulator. The plunger A forms 85 part of the bag-turning machine, and it also serves as a feeder for transmitting the bag from the bag-turning mechanism to the accumulator.

I will now refer to a bag-opening member 90 in the form of a blade 46, which is shown most clearly in Figs. X, XI and XII. After the bag X has been turned, and after the bag-receiving arms 1 and 2 have been displaced from their bag-turning positions, the blade 46 enters the mouth of the bag and moves downwardly to the position shown by Fig. XII, for the purpose of forcibly opening the mouth of the bag, which is then supported on the plunger A. The cooperative 95 action of the plunger A and arms 1 and 2 does not always completely turn the corners at the mouths of the bags, and the function of the blade 46 is to forcibly open the bags, as shown by Fig. XII, for the purpose of 100 removing wrinkles from these corners of the bags.

The bag-opening blade 46 is secured to an approximately horizontal plate 47 (Figs. X, XI and XII) and this plate 47 is supported 105 by a pair of parallel arms 48 and 49 on the reciprocating carriage C. The arm 49 is pivoted to the carriage C through the medium of a pivot rod 49' (Figs. XI and XII), and the arm 48 is secured to a pivot rod 48' which is also mounted in the carriage C. The upper end of arm 48 is attached to the plate 47 by means of a pivot pin 50, and the upper end of arm 48 is provided with a pin 51 which extends into a 110

slot 52 in the plate 47. A spring 53 connects the pin 50 to the pin 51, as shown by Figs. XI and XII, and this spring yieldingly retains the pivot pin 51 in the right-hand end of the slot 52 in the plate 47. The pin 51 normally lies in this end of the slot and it is only under unusual conditions that said pin occupies any other position relative to the slot, so the pin 51 may be considered 10 as a pivotal connection between the arm 48 and the plate 47. The purpose of the spring 53 and slot 52 will be hereafter described. To shift the bag-opening blade 46 to the position shown by Fig. XII, an operating 15 arm 54 (Figs. XI and XII) is secured to the pivot rod 48' on which the arm 48 is secured. From the foregoing it should be understood that if the operating arm 54 is moved downwardly from the position shown 20 by Fig. XI, the arm 48 will move forwardly and downwardly, and a corresponding movement will be imparted to the arm 49, for these arms 48 and 49 are secured to the plate 47 through the medium of pivot pins 50 and 25 51, and the spring 53 tends to retain the pivot pin 51 in a fixed position relative to the pin 50. Therefore, when the operating arm 54 is moved downwardly from the position shown by Fig. XI, the plate 47 will 30 move forwardly and downwardly, the object being to impart a movement of this kind to the bag-opening blade 46 which is inserted into the mouth of the bag and then moved to the position shown by Fig. XII. 35 The operating arm 54 is provided with a roller at 55 adapted to travel along a horizontal track 56 leading to a downwardly extending cam slot 57, said slot being formed in a bracket 58 which is secured to a stationary part of the frame by means of bolts 59 shown in Figs. X and XI.

During each bag-turning operation, the reciprocating carriage C moves to the left from the position shown by Figs. X and XI, 45 and the arms 48, 49 and 54 are carried by this reciprocating carriage. As a consequence, the roll on the end of arm 54 travels to the left along the track 56 and then into the cam slot 57, whereby said arm 54 is 50 thrown forwardly and downwardly to the position shown by Fig. XII. Motion is thus transmitted from the operating arm 54 to the bag-opening blade 46 so as to shift said blade to the position shown in Fig. 55 XII. The blade 46 enters the mouth of the bag and then moves downwardly to forcibly open the bag, as previously pointed out, for the purpose of removing wrinkles of the corners at the mouth of the bag.

60 Under some unusual conditions, the bag-turning plunger A may fail to properly turn the bag. For example, a bag may be improperly applied to the arms 1 and 2, so that its closed end will hang from said 65 arms, or a bag may not be slipped over all

of the arms 1 and 2, it being understood that there are four of these arms. If a bag is thus improperly applied to the arms 1 and 2, the plunger A may be forced through a portion of the bag and fail to turn the same. In this event the bag-opening blade 46 will strike the mutilated bag, and since breakage may result from a continued forward motion of the blade, said blade is 70 yieldingly secured to the cam-actuated arm 54. This yielding securing means includes the spring 53 (Fig. XI) whereby the pivot 50 is connected to the pivot 51, the latter being in the slot 52. By mounting the blade 46 on a yielding support of this kind, the cam-actuated arm 54 can move downwardly 75 without imparting a forward motion to the blade 46 when the latter is stopped by engaging a mutilated bag on the arms 1 and 2.

Before pointing out the details of the accumulator shown in the drawings, I will state that this device comprises a rotary drum provided with a series of radial bag-holders, in the form of grippers, which are 80 adapted to hold a collection of bags. The drum is turned step by step to successively locate the grippers in alinement with the bag-turning plunger which forces the closed ends of the bags into the grippers. After a predetermined number of bags have been 85 delivered to a gripper, the rotary drum is advanced one step to displace the collection of bags from the path of the bag-turning plunger and to locate an empty gripper at 90 said path. This device also includes means for opening the grippers to provide for the admission of the bags, and means whereby 95 the operations of the bags are deflected downwardly from the grippers to points entirely below the path of the bag-turning 100 plunger.

D designates a rotary drum comprising a pair of circular side plates 60 connected together through the medium of rods 61, said drum being fixed to a shaft 62 rotatably 110 mounted in bearings 63. The series of bag-holders is formed by radial grippers located between the side plates 60 of the drum. Each gripper comprises a rigid gripping jaw 64 (Figs. II and III) which may be 115 made of a pair of approximately flat plates having ears through which the connecting rods 61 are inserted. These rods 61 rigidly secure the rigid jaws 64 to the rotary drum D. Each gripper also includes a series of yielding jaws 65 (Figs. II and III) and each jaw 65 is in the form of a lever fulcrumed on a pivot pin 66 at the free end of an arm 67, said arm being supported by a pivot pin 68 (Fig. II) carried by the rotary drum. Each arm 67 may be moved about the axis of its pivot 68, and each yielding gripper jaw 65 is movable about its fulcrum or pivot 66. Each arm 67 is provided with an extension 67' (Fig. II), and a spring 69 is in- 120 125 130

terposed between this extension and a similar extension on a rigid jaw 64. In Figs. II, X and XII, X' designates a collection of bags hanging from one of the gripping devices, and X² designates larger collections of bags hanging from other gripping devices. The collection X' is located at the path of the bag-turning plunger A, and the gripping device which holds this collection of bags is located in its bag-receiving position, said gripping device being in alinement with the plunger A. Upon the completion of a bag-turning operation, the plunger A enters the last mentioned gripping device so as to force the closed end of a bag between its gripping jaws 64 and 65. Immediately before a bag is forced into a gripping device, the yieldingly mounted lower gripping jaw 65 is actuated to open the gripping device. In this connection note that each gripping jaw 65 is in the form of a lever adapted to contact with the bags at points on opposite sides of the lever fulcrum 66, so the outer end of a gripping jaw 65 may be depressed to open the gripping device without releasing the bags. When the outer end of a gripping jaw 65 is forced away from its companion jaw 64, the inner end of jaw 65 will firmly contact with the collection of bags, so as to securely hold the same. The inner end of each gripping jaw 65 is preferably rounded as shown in Fig. II, and this rounded portion contacts with the collection of bags when the outer end of the jaw is forced downwardly. The outer ends of the companion jaws 65 and 64 are preferably flared away from each other to provide a relatively wide intake for the gripping device. The means for opening the grippers preferably includes a pair of pressure fingers 70 shown in Figs. II, IV, and VI, said fingers being adapted to overlie the collection of bags X' in the gripping device which is positioned in the path of the bag-turning plunger. These pressure fingers, or opening fingers, are secured to operating rods 71 at opposite sides of the last mentioned gripping device, and said fingers extend over the yieldable lower jaws 65 of said gripping device. Before describing the details of the mechanism for actuating the fingers 70, I will briefly describe the peculiar movements which are imparted to these fingers. Immediately before a bag is delivered to the gripping device, the fingers 70 move downwardly and they press upon the top bag in the collection X' (Fig. II) so as to move the outer end of gripping jaw 65 away from the rigid gripping jaw 64. The fingers 70 are thus shifted to points entirely below the path of the bag-turning plunger where they hold the gripping jaw 65 in its open position, while the bag is being inserted into the gripping device. Thereafter, the bag turning plunger A is withdrawn from the grip-

ping device, and also from the bag, the latter being secured by the gripping jaws. The last mentioned bag then extends over the fingers 70, and it is necessary to withdraw these fingers from the bags. The fingers 70 therefore move away from each other to positions entirely beyond the bags, and they then move upwardly and toward each other so as to again overlie the collection of bags, as will be presently described. 75

The means for operating the fingers 70 is shown in Figs. I, III and IV. These fingers are rigidly secured to the approximately vertical rods, or arms 71, and the lower ends of these rods are loosely connected to a horizontal bar 72 (Fig. IV), said bar having slots 73 for the reception of pivot pins 74 whereby the rods 71 are loosely secured. The bar 72 is rigidly secured to a vertical rod 75 slidably mounted in a stationary 80 guide 76 which is shown in Figs. I, III and IV. The upper end of rod 75 is provided with a roll which engages a rotary cam 77. A spring 78 at the lower end of rod 75 tends to retain the roll in engagement with the 85 cam 77. This cam is fixed to the rotary shaft 39, which has already been described. By referring to Fig. IV it will be seen that the rod 75 will move vertically in response to a rotary motion of the cam 77, and that a 90 corresponding vertical motion will be imparted to the bar 72 to which the rods 71 and fingers 70 are loosely secured. However, the fingers 70 must be moved away from each other to withdraw them from the bags. 95 The rods 71 are therefore slidably mounted in tubular guides 79 (Figs. I and IV), each of said guides being fixed to an oscillatory arm 80 pivotally supported at 81. The inner ends of arms 80 (Fig. IV) are provided with gear teeth which mesh with each other, so that motion may be transmitted from one arm 80 to the other arm 80. One of the oscillatory arms 80 is provided with an operating arm 82 (Fig. IV) having a roller which 100 engages a cam 83 on the rotary shaft 39. A spring 84 (Fig. IV) is connected to one of the oscillatory arms 80 for the purpose of retaining the operating arm 82 in engagement with the cam 83. 105

The gripper-opening fingers 70 are operated as follows: The fingers 70 are moved from the highest position shown by dotted lines in Fig. IV to the lower position shown by full lines, and this is accomplished 110 through the medium of the cam 77 which depresses the rod 75 to impart downward motion to the bar 72 and rods 71 on which the fingers 70 are mounted. After a bag has been delivered to the gripping device, the 115 fingers 70 are moved away from each other and withdrawn from the space between the top bag and the next adjacent bag. The fingers are moved away from each other through the medium of the oscillatory arms 120 130

80 to which the tubular guides 79 are rigidly secured. The cam 83 acts upon the operating arm 82 to impart upward motion to the arms 80, thereby forcing the fingers 70 away from each other, as suggested by dotted lines in Fig. IV. After the fingers have been withdrawn from the bags, they are moved upwardly and toward each other, so as to occupy the highest positions shown by dotted lines in Fig. IV. The upward motion of the fingers is derived from the spring 78 at the bottom of Fig. IV, said spring acting upon the rod 75 which engages the cam 77. The fingers are moved toward each other through the medium of spring 84 which acts upon the oscillatory arms 80 to move the fingers when the cam-actuated arm 82 is permitted to move toward the shaft 39.

The bags are delivered one at a time to the gripping device, and after being delivered they should hang from the gripping device so that the collection of bags will not in any way interfere with the admission of the bags which are subsequently delivered by the bag-turning plunger.

For this reason, each opening-finger 70 is provided with a downturned extension 70' (Figs. II and IV) serving as a deflector whereby portions of the bags extending from the gripping device are positively forced downwardly near the outer extremity of the gripping device. The collection of bags X' is also acted upon by a smoothing device in the form of a blade 86, shown in Figs. X, XI and XII, said blade having a straight edge adapted to engage the collection of bags X'. The smoothing blade 86 is rigidly secured to the plate 47 which is carried by the reciprocating carriage C, to which the bag-turning plunger is secured. I have already described the means whereby the plate 47 is moved from the position shown in Fig. XI to the position shown in Fig. XII. This plate 47 is secured to the arms 48 and 49, which are pivoted to the carriage C and which are thrown forwardly and downwardly by the operating arm 54 while the roller on said arm is traveling in the cam slot 57. The smoothing blade 86 therefore engages the collection of bags X' so as to force said bags to the left from the position shown in Fig. X, and at the same time this blade 86 moves downwardly to the position shown in Fig. XII, with the result of drawing the collection of bags downwardly and at the same time smoothing them above the blade 86. The collection of bags at X' is thus smoothed and compacted immediately after each bag-turning operation, so as to neatly arrange the collection of bags and at the same time prevent the bags from obstructing the path of the bag-turning plunger A.

The rotary drum D, which carries the series of bag-holding grippers, is normally

locked through the medium of a horizontal bolt 87 (Figs. I, III and XI), said bolt being slidably mounted in guides 88 which are shown in Fig. III. One side of the rotary drum is provided with a series of bolt-receiving holes 89 and lugs 90 adjacent to one side of each hole. The lugs are shown in Figs. VI and XI. One hole 89 is formed for each gripping device in the drum D, and when the horizontal locking bolt 87 is located in one of the holes, one of the gripping devices is positioned at the path of the bag-turning plunger. As shown in Fig. III, a spring 91 is interposed between one of the stationary bearings 88 and a collar 92 on the locking bolt 87, and this spring tends to retain the locking bolt in its operative position. The collar 92 is extended upwardly, as shown in Figs. III and XIV, to provide an operating finger adapted to be engaged by an unlocking cam 93 which will be hereafter described. When this cam 93 passes the unlocking finger on the collar 92, the cam operates with the finger to shift the locking bolt 87, thereby unlocking the rotary drum D.

The means for turning the rotary drum D includes a ratchet wheel 94 fixed to the shaft 62 on which the drum is mounted. Figs. VIII and XI show that the ratchet wheel 94 is keyed to the shaft 62, so said shaft and the drum may be turned by the ratchet wheel 94. The hub of an arm 96 is loosely mounted on the shaft 62. A pawl 97, pivoted to the arm 96, as shown by Fig. XIV, is adapted to engage the ratchet wheel 94, but this pawl is normally engaged with the periphery of a disk 98 whereby it is prevented from engaging the teeth of the ratchet wheel. The pawl-carrying arm 96 (Figs. III, XIII and XIV) is oscillated through the medium of a substantially vertical rod 99 having its upper end pivoted to said arm, the lower end of rod 99 being pivoted to an operating lever 100 provided with a roll adapted to engage a cam 101 on the rotary shaft 39. The lever 100 is pivotally supported at 102, as shown by Figs. III and XIII. The operating lever 100 is forced downwardly through the medium of the cam 101 and it is restored through the medium of a rod 103 provided with a collar 104 (Fig. III), which is engaged by a spring 105. This spring tends to force the rod 103 and lever 100 in an upward direction, thereby retaining the lever 100 in engagement with the cam 101. During each operation of the bag-turning mechanism, the shaft 39 makes one revolution, and since the pawl-carrying arm 96 (Figs. XIII and XIV) is operated by the cam 101 on shaft 39, it will be understood that this pawl-carrying arm 96 will oscillate in response to each bag-turning operation. However, if the pawl 97 (Fig. XIV) is engaged with the pe-

riphery of the disk 98, said pawl will move idly without transmitting motion to the ratchet wheel 94. This disk 98 is provided with a notch 106 (Fig. XIV), and when the 5 operating end of pawl 97 registers with this notch, the pawl will be permitted to engage a tooth on the ratchet wheel 94, and if the pawl-carrying arm 96 is then oscillated, the pawl will transmit motion to the 10 ratchet wheel, so as to advance the rotary drum D one step. The pawl-carrying arm 96 is provided with a spring 107 (Fig. XIV) which engages the pawl 97 and which tends to force the pawl into engagement with the 15 ratchet wheel 94.

From the foregoing it will be understood that the pawl 97 is oscillated in response to each bag-turning operation, and that said pawl cannot transmit motion to the rotary 20 drum on the shaft 62 until the notch 106 registers with the operating end of the pawl. This notch 106 is formed in the disk 98 which moves step by step around the shaft 62, said disk moving one step in response to each bag-turning operation. Therefore, during each revolution of the 25 disk 98, the drum D on the shaft 62 will be advanced one step, so as to displace a collection of bags from the path of the bag-turning plunger A and at the same time locate an empty gripping device at said path. The 30 disk 98 is operated through the medium of counting mechanism, the object being to deliver a predetermined number of bags to 35 each gripping device in the rotary drum. When a predetermined number of bags, for example, twenty-five, has been delivered to a gripping device, the notch 106 (Fig. XIV) registers with the pawl 97 to permit operation 40 of the ratchet 94.

The means for imparting a step by step motion to the disk 98 comprises a ratchet wheel 108 (Figs. I, III, XV and XVII), loosely mounted on a collar 109 on the drum-carrying shaft 62, said ratchet wheel being secured to the disk 98 through the medium of a screw 110 which is shown in Fig. XV. The ratchet wheel 108 is driven through the medium of a pawl 111 (Figs. VII and XVII) on an oscillatory arm 112 having a hub which is loosely mounted on a bushing 113 at one end of the drum-supporting shaft 62. The oscillatory pawl-carrying arm 112 is driven through the medium of a connecting rod 114 having its upper end pivoted to said arm and its lower end pivoted to an operating lever 115 which is shown most clearly in Fig. XVI, the operating lever being pivotally supported at 116 and provided 55 with a roll engaged by a cam 117 on the constantly rotating shaft 39. As shown by Figs. I and XVI, a rod 118 depending from the lever 115 is provided with a collar 119 engaged by a spring 120, which tends to 60 force the rod 118 in an upward direction,

thereby retaining the lever 115 in engagement with the cam 117. During each bag-turning operation, the operating lever 115 (Fig. XVI) is actuated and motion is thus transmitted through the connecting rod 114 70 to the oscillatory pawl-carrying arm 112, which cooperates with the ratchet wheel 108 to shift the notched disk 98, the latter being shown in Figs. XIV and XV. The notched disk 98 therefore travels step by step in response to the corresponding movements of the ratchet wheel 108, said ratchet wheel being advanced one step in response to each bag-turning operation so as to serve as means for counting the bags transmitted to 75 the bag-holding grippers. After a predetermined number of bags has been delivered to a gripper, the pawl 97 (Fig. XIV) registers with the notch 106 so as to engage the ratchet wheel 94, whereby the rotary drum is shifted to displace the predetermined collection of bags from the path of the bag-turning plunger.

Immediately before the drum is shifted it must be unlocked, and this is accomplished as follows: In Figs. III, XI and XIV I have shown the spring-pressed locking bolt 87 which normally lies in one of the holes 89 in the drum to retain said drum in a fixed position. The disk 98 (Figs. III, XIII and XIV) is provided with a cam 93 which has been previously referred to, and this cam is adapted to engage an unlocking finger 92 on the bolt 87 for the purpose of unlocking the bolt. When the pawl 97 enters the notch 106 (Fig. XIV) the pawl is forced downwardly with the result of simultaneously operating the disk 98 and the ratchet wheel 94. More accurately stated, the pawl 97 first actuates the disk 98 to shift the unlocking cam 93 into engagement with the unlocking finger 92, thereby unlocking the rotary drum, and immediately thereafter the pawl 97 engages a tooth on the ratchet wheel 94, so as to simultaneously actuate the ratchet 94 and disk 98. When the cam 93 passes from the unlocking finger 92, the spring-pressed bolt 87 (Figs. III and XI) is yieldingly forced into engagement with a side face of the drum D, and as the drum continues in motion, one of its lugs 90 will strike the spring-pressed bolt 87. At this time the bolt 87 will register with one of the bolt-receiving openings 89 and the bolt will be forced into this opening so as to again lock the drum in a 105 fixed position.

The notched disk 98 is secured to the ratchet wheel 108 through the medium of a screw 110 (Fig. XV) as previously pointed out, and the ratchet device including the wheel 108 serves as means for imparting a step by step movement to the notched disk for the purpose of counting the bags, but this notched disk is also moved through the medium of pawl 97 (Fig. XIV) during the op- 110 115 120 125 130

eration of shifting the rotary drum, and whenever the disk is actuated by the pawl 97, the ratchet wheel 108 will turn with said disk. It is therefore unnecessary to form 5 teeth on the entire periphery of the ratchet wheel 108 (Fig. XVI). When the plain arcuate peripheral portion of ratchet wheel 108 reaches a point adjacent to the pawl 111, the notch 106 (Fig. XIV) lies adjacent to 10 the pawl 97, and the disk 98 and ratchet wheel 108 are then turned through the medium of the pawl 97, so as to idly move the plain peripheral face of disk 108 (Fig. XVII) across the pawl 111. Of course, the 15 ratchet wheel could be provided with teeth throughout its entire circumference, but in this event some of the teeth would perform no useful function.

This explanation is given to account for the 20 untoothed peripheral portion of ratchet wheel 108.

I have stated that the ratchet wheel 108 is adapted to move one step in response to each 25 bag-turning operation, so as to count the bags passing to the grippers, but this ratchet wheel is driven through the medium of a cam 117 (Fig. XVI) on the constantly rotating shaft 39, which makes one revolution during each complete operation of the bag- 30 turner. Bags are usually delivered to the bag-turning mechanism by an operator who occasionally fails to deliver a bag when the mechanism is positioned to receive the same. Consequently, the bag-turning mechanism is 35 frequently operated when there is no bag delivered to the path of the bag-turning plunger. This being true, the counting mechanism should not depend entirely upon the motion of the bag-turning mechanism, the 40 object being to accurately count the bags, irrespective of the number of strokes of the bag-turning device.

With this object in view, I have shown a 45 controller for the counting means including an operating member adapted to be actuated by the bags passing to the drum D. Before describing the details of this controlling device I will state that it includes a guard, or shield, adapted to prevent effective operation 50 of the counting ratchet, and an operating member located in the path of the bags, said operating member being shifted by the bags so as to shift the guard, or shield, thereby permitting operation of the counting 55 mechanism when a bag is passing to the rotary drum. The guard, or shield, comprises a segmental member 121 (Figs. VII and VIII) located adjacent to the ratchet wheel 108 and loosely mounted on the collar 109, said member 121 having an arcuate guard flange 122 which extends over a portion 60 of the ratchet wheel 108. This shield may be oscillated about the axis of shaft 62, but it normally occupies the position shown 65 by full lines in Fig. VII, where the guard

flange 122 lies between the pawl 111 and the ratchet wheel 108. When the guard flange occupies this position, the pawl 111 can be shifted without transmitting motion to the ratchet wheel 108. The guard 121— 70 122 must be shifted to the position shown by dotted lines in Fig. VII to permit transmission of motion from pawl 111 to ratchet wheel 108. The means for shifting this guard comprises an operating finger 123 (Figs. I, VI and VII) located adjacent to the bag-turning plunger A, said plunger being slotted at 124 (Fig. VI) to receive the lower portion of finger 123. It is important 75 to observe that this operating finger 123 lies adjacent to but beyond the path of the bag- turning plunger A, so that said plunger can be operated without transmitting motion to the finger 123. However, when a bag is carried by the plunger said bag completely 80 covers the slot 124, and motion is transmitted from the bag to the finger 123, so as to shift said finger from the position shown by full lines in Fig. VII, to the position shown by dotted lines. The means for 85 transmitting motion from finger 123 to the guard 121—122 includes oscillatory shaft 125 to which said finger is rigidly secured, an arm 126 depending from said shaft, and a rod 127 whereby said arm is connected to the segmental guard 121—122. 90

From the foregoing it will be readily understood that the bag-turning plunger can be reciprocated without displacing the operating finger 123 (Figs. VI and VII) and without displacing the guard 121—122 from the position shown by Fig. VII. In this event the pawl 111 (Fig. VII) will be shifted through the medium of its operating mechanism which moves in synchronism with the bag-turning plunger, but said pawl will not transmit motion to the counting ratchet 108. However, when a bag is being delivered by the bag-turning plunger A, said 100 bag will strike the operating finger 123 and displace the same to the position shown by dotted lines in Fig. VII, thereby moving the guard 121—122 to the position shown by dotted lines and permitting the pawl 111 to 105 engage the counting ratchet 108. The pawl 111 will then transmit motion to the counting ratchet, so as to count the bag. 110

Although I have shown and described the invention in connection with a bag-turning machine, it is to be understood that the invention herein disclosed is not limited to such use. The bags are in the form of folded sheets, and it will be understood that other kinds of sheet material could be transmitted to the accumulator. However, numerous advantages are gained by combining the accumulator with a bag-turning device, so as to accurately count the bags and at the same time neatly arrange them in 120 predetermined collections which can be 125 130

readily baled or otherwise packed for shipment with very little labor on the part of the operator.

I claim:

5. 1. An accumulator comprising a sheet-holder provided with a sheet-gripper wherein the sheets accumulate, said sheet-gripper comprising a pair of gripping jaws adapted to receive margins of a collection of sheets 10 and a spring tending to force one of said jaws toward the other, means for feeding said margins of the sheets into said sheet-gripper, and means whereby said sheet-gripper is shifted in response to a predetermined 15 number of sheet-feeding operations.
2. In a sheet-counting apparatus, an accumulator comprising a series of sheet-grippers each of which is adapted to hold a collection of sheets, a feeder including a reciprocating sheet-pusher whereby margins of the sheets are pushed into said sheet-grippers, said sheet-grippers being shiftable step by step to successively align them with said sheet-pusher, and counting means whereby 20 said grippers are shifted in response to a predetermined number of sheet-feeding operations.
3. In a sheet-counting apparatus, an accumulator comprising a rotary drum provided with a series of radial sheet-grippers each of which is adapted to hold a collection of the sheets, a feeder including a reciprocating sheet-pusher whereby margins of the sheets are pushed into said sheet-grippers, 30 said rotary drum being movable step by step to successively align the sheet-grippers with said sheet-pusher, and counting means whereby said rotary drum is shifted in response to a predetermined number of sheet-feeding operations.
4. An accumulator comprising a sheet-holder provided with a sheet-gripper, an opening device whereby said sheet-gripper is opened to receive margins of the sheets, 40 a sheet-feeder co-operating with said opening device to deliver sheets to said sheet-holder, and means whereby said sheet-holder is shifted in response to a predetermined number of sheet-feeding operations.
5. An accumulator comprising a sheet-holder provided with a sheet-gripper adapted to hold a collection of sheets, an opening device whereby said sheet-gripper is opened to receive margins of the sheets, a sheet-feeder 50 cooperating with said opening device to deliver sheets to said sheet-holder, and counting means whereby said sheet-holder is shifted in response to a predetermined number of sheet-feeding operations.
6. An accumulator comprising a sheet-holder provided with a sheet-gripper adapted to hold a collection of sheets, an opening device whereby said sheet gripper is opened to receive margins of the sheets, said opening device including a pressure member 60
- whereby the sheets are held when the gripper is open, a sheet-feeder cooperating with said opening device to deliver sheets to said sheet-holder, and means whereby said sheet-holder is shifted in response to a predetermined number of sheet-feeding operations. 70
7. An accumulator comprising a sheet-holder provided with a sheet-gripper adapted to hold a collection of sheets, said sheet-gripper including a yieldable gripping jaw, 75 an opening device whereby said sheet-gripper is opened to receive margins of the sheets, said opening device including a pressure member which cooperates with said yieldable jaw to hold the sheets when the gripper is open, a sheet-feeder cooperating with said opening device to deliver sheets to said sheet-holder, and means whereby said sheet-holder is shifted in response to a predetermined number of sheet-feeding operations. 80
8. An accumulator comprising a sheet-holder provided with a sheet-gripper adapted to receive margins of a collection of sheets, an opening device whereby said sheet-gripper is opened to receive said margins, a sheet-feeder cooperating with said opening device to deliver sheets to said sheet-holder, said sheet-feeder including a sheet-pusher movable over the margins of the sheets in 90 said sheet-gripper, and said opening device including a pressure member whereby said margins of the sheets are displaced and held below the path of said sheet-pusher.
9. An accumulator comprising a sheet-holder provided with a sheet-gripper adapted to hold a collection of sheets, an opening device whereby said sheet-gripper is opened to receive margins of the sheets, said opening device including a pressure member 100 adapted to engage the top sheet of the collection, a sheet-feeder movable over said pressure member to deliver the sheets to said holder, and means for withdrawing said pressure member from the sheets. 105
10. An accumulator comprising a sheet-holder provided with a sheet-gripper adapted to hold a collection of sheets, an opening device whereby said sheet-gripper is opened to receive margins of the sheets, said opening device including a pressure member adapted to engage the top sheet of the collection, a sheet-feeder movable over said pressure member to deliver the sheets to said holder, and means whereby said pressure member is shifted laterally from the sheets 115 and thereafter restored to engage the top sheet.
11. An accumulator comprising a sheet-holder provided with a sheet gripper adapted to hold margins of a collection of sheets, an opening device comprising a pair of pressure members located at opposite sides of the gripper and adapted to press upon the top sheet to open the gripper, a sheet feeder 125
- 65 130

whereby margins of the sheets are fed over said pressure members and into said gripper, and operating means whereby said pressure members are moved away from each other and thereafter restored to engage the top sheet.

12. An accumulator comprising a sheet-holder provided with a sheet gripper adapted to hold margins of a collection of sheets, 10 an opening device comprising a pair of pressure members located at opposite sides of the gripper and adapted to press upon the top sheet to open the gripper, a sheet feeder whereby margins of the sheets are fed over 15 said pressure members and into said gripper, and operating means whereby said pressure members are moved away from each other and thereafter restored to engage the top sheet, said operating means including 20 mechanism whereby said pressure members are elevated and moved toward each other after they have been moved away from each other.

13. An accumulator comprising a sheet-holder provided with a sheet gripper adapted to hold margins of a collection of sheets, 25 an opening device comprising a pair of pressure members located at opposite sides of the gripper and adapted to press upon the top sheet to open the gripper, a sheet feeder whereby margins of the sheets are fed over 30 said pressure members and into said gripper, said gripper including a yieldable lower gripping jaw below said pressure members, 35 and operating means whereby said pressure members are forced downwardly on the top sheet to displace said yieldable lower gripping jaw, said operating means also including mechanism whereby said pressure members are moved away from each other to 40 shift them from the sheets and thereafter moved upwardly and toward each other, so as to overlie the top sheet.

14. An accumulator comprising a sheet-holder provided with a sheet gripper adapted to hold margins of a collection of sheets, 45 an opening device comprising a pair of opening fingers located at opposite sides of the gripper and adapted to press upon the top sheet to open the gripper, operating arms to which said opening fingers are secured, a pivotal support for said operating arms, means for lowering and raising said pivotal support, rockable guides for said 50 operating arms, means for rocking said guides to withdraw and restore said opening fingers relative to the sheets, and a sheet-feeder whereby margins of the sheets are fed over said opening fingers while said 55 pivotal support occupies its low position.

15. An accumulator comprising a sheet-holder provided with a sheet-gripper adapted to receive margins of the sheets, said gripper including a gripping jaw in the 60 form of a lever adapted to contact with a

sheet at opposite sides of the lever fulcrum, and means whereby said margins of the sheets are forced into said gripper.

16. An accumulator comprising a sheet-holder provided with a sheet-gripper adapted to receive margins of the sheets, said gripper including a gripping jaw in the form of a lever adapted to contact with a sheet at opposite sides of the lever fulcrum, 70 an opening device whereby the outer end of the lever is shifted to open the gripper, and a sheet feeder whereby margins of the sheets are forced into the gripper while said opening device is effective.

17. An accumulator comprising a sheet-holder provided with a sheet-gripper adapted to receive margins of the sheets, said gripper including a gripping jaw in the form of a lever adapted to contact with a sheet at opposite sides of the lever fulcrum, 75 the outer end of said gripping jaw being yieldable about said fulcrum to permit opening of the gripper without releasing the inner end of the jaw from the sheet, an opening device whereby said outer end is shifted to open the gripper, and a feeder whereby margins of the sheets are forced into said gripper while said opening device is effective.

18. An accumulator comprising a sheet-holder provided with a sheet-gripper adapted to receive margins of the sheets, said gripper including a gripping jaw in the form of a lever, a yieldable arm to which said lever is fulcrumed, said lever being adapted to contact with the sheet at points on opposite sides of the fulcrum, and means whereby said margins of the sheets are forced into said gripper.

19. An accumulator comprising a sheet-holder provided with a sheet-gripper adapted to receive margins of a collection of sheets, said gripper including a gripping jaw in the form of a lever adapted to contact at two points on the lowermost sheet, a pivotally supported arm, a pivot whereby said arm is connected to said lever at a point between the two points of contact, a spring cooperating with said pivotally supported arm to yieldingly retain said lever in contact with the collection of sheets, and a feeder including a pusher whereby margins of the sheets are forced into said sheet-gripper.

20. An accumulator comprising a sheet-holder provided with a sheet-gripper from which the sheets are suspended, said gripper being adapted to receive the upper margins of a collection of the sheets, a feeder whereby the sheets are delivered to said gripper, and a deflector whereby the sheets are forced downwardly from the path of said feeder.

21. An accumulator comprising a sheet-holder provided with a sheet-gripper from

which the sheets are suspended, said gripper being adapted to receive the upper margins of a collection of the sheets, a feeder whereby the sheets are delivered to said gripper, 5 and an opening device whereby said gripper is opened to receive the sheets, said opening device being provided with a deflector whereby portions of the suspended sheets are deflected to points below the path of 10 said feeder.

22. An accumulator comprising a sheet-holder provided with a sheet-gripper from which the sheets are suspended, said gripper being adapted to receive the upper margins 15 of a collection of the sheets, a feeder whereby the sheets are delivered to said gripper, and an opening device whereby said gripper is opened to receive the sheets, said opening device being provided with a down-turned extension whereby portions of the suspended sheets are deflected to points below the path of said feeder.

23. An accumulator comprising a sheet-holder provided with a sheet-gripper adapted 25 to hold a collection of sheets, an opening device whereby said sheet-gripper is opened to receive margins of the sheets, said opening device including a pressure member adapted to engage the top sheet of the collection, a sheet-feeder movable over said pressure member to deliver the sheets to said holder, and a deflector extending downwardly from said pressure member to deflect portions of the sheets to points below 30 the path of said feeder.

24. An accumulator comprising a sheet-holder provided with a sheet gripper adapted to hold margins of a collection of sheets, an opening device comprising a pair of pressure members located at opposite sides of 40 the gripper and adapted to press upon the top sheet to open the gripper, a sheet feeder whereby margins of the sheets are fed over said pressure members and into said gripper, and deflectors extending downwardly from said pressure members to deflect portions of the sheets to points below the path of said sheet-feeder.

25. An accumulator comprising a sheet- 50 holder provided with a sheet-gripper from which the sheets are suspended, said gripper being adapted to receive the upper margins of a collection of the sheets, a feeder whereby the sheets are delivered to said gripper, and means whereby depending portions of 55 the suspended sheets are drawn downwardly from said gripper.

26. An accumulator comprising a sheet- 60 holder provided with a sheet-gripper from which the sheets are suspended, said gripper being adapted to receive the upper margins of a collection of the sheets, a feeder whereby the sheets are delivered to said gripper, and means whereby depending portions of 65 the suspended sheets are drawn downwardly

from said gripper, said means including a smoothing device movable downwardly on the outer face of the collection of sheets.

27. An accumulator comprising a sheet-holder provided with a sheet-gripper from 70 which the sheets are suspended, said gripper being adapted to receive the upper margins of a collection of the sheets, a feeder whereby the sheets are delivered to said gripper, means for reciprocating said feeder, a 75 smoothing device adapted to engage the collection of sheets at points below said feeder, and means for imparting a downward motion to said smoothing device.

28. An accumulator comprising a sheet-holder provided with a sheet-gripper from which the sheets are suspended, said gripper being adapted to receive the upper margins 80 of a collection of the sheets, a feeder whereby the sheets are delivered to said gripper, said feeder including a reciprocating pusher adapted to force margins of the sheets into said gripper, a smoothing device adapted to engage the collection of sheets at points below the path of said pusher, and means for 85 imparting a downward motion to said smoothing device.

29. An accumulator comprising a sheet-holder provided with a sheet-gripper from which the sheets are suspended, said gripper being adapted to receive the upper margins 90 of a collection of the sheets, a feeder whereby the sheets are delivered to said gripper, said feeder including a pusher adapted to force margins of the sheets into said gripper, a smoothing device adapted to engage the collection of sheets at points below the path of said pusher, and means for reciprocating 95 said pusher and smoothing device.

30. An accumulator comprising a sheet- 100 holder provided with a sheet-gripper from which the sheets are suspended, said gripper being adapted to receive the upper margins of a collection of the sheets, a feeder whereby the sheets are delivered to said gripper, said feeder including a pusher adapted to force margins of the sheets into said gripper, a smoothing device adapted to engage the collection of sheets at points below the path 105 of said pusher, means for reciprocating said pusher and smoothing device and a cam whereby said smoothing device is forced downwardly while it engages the collection 110 of sheets.

31. An accumulator comprising a sheet- 115 holder provided with a sheet-gripper from which the sheets are suspended, said gripper being adapted to receive the upper margins of a collection of the sheets, a feeder whereby the sheets are delivered to said gripper, said feeder including a pusher adapted to force margins of the sheets into said gripper, a smoothing device adapted to engage the collection of sheets at points below the path 120 of said pusher, and means for reciprocating 125 said pusher, and means for reciprocating 130

said pusher and smoothing device, said means including a reciprocating carriage to which said smoothing device is yieldingly secured.

32. An accumulator comprising a sheet-holder wherein the sheets accumulate, a sheet-feeder whereby the sheets are successively delivered to said sheet-holder, counting means whereby said sheet-holder is shifted from said sheet-feeder in response to a predetermined number of feeding operations, said counting means including a ratchet and pawl movable one step in response to an operation of said sheet-feeder, and a controller for said counting means, said controller including a device adapted to render the ratchet and pawl inoperative so as to prevent transmission of motion to said counting means, and an operating member whereby said device is displaced to permit transmission of motion to said counting means, said operating member being located in the path of the sheets passing to said sheet holder.

33. In a sheet-counting apparatus, an accumulator comprising a series of sheet-holders each of which is adapted to receive a collection of sheets, a feeder whereby the sheets are delivered to said sheet-holders, said sheet-holders being movable step by step to successively receive the collections of sheets transmitted from said feeder, counting means whereby said sheet-holders are shifted in response to a predetermined number of sheet-feeding operations, and a controller for said counting means, said controller including an operating member adapted to be displaced by the sheets.

34. In a sheet-counting apparatus, an accumulator comprising a carrier, a series of sheet-holders carried by said carrier, each of said sheet holders being adapted to receive a collection of sheets, a reciprocating feeder whereby the sheets are delivered to said sheet-holders, said carrier being movable step by step to successively locate the sheet-holders in the path of said reciprocating feeder, counting means including a ratchet wheel adapted to impart a step by step movement to said carrier, an oscillatory pawl adapted to engage said ratchet wheel, said oscillatory pawl being movable in response to each operation of said reciprocating feeder, a shield whereby said pawl is normally retained in a position beyond said ratchet wheel, a second ratchet wheel whereby motion is transmitted to said shield, a second pawl adapted to actuate said second ratchet wheel, a second shield adapted to prevent engagement of said second pawl and ratchet wheel, said second pawl being movable in response to each operation of said feeder, and a controller for said second shield, said controller including an operating member

located adjacent to said feeder, and said operating member being in the path of the sheet transmitted by said feeder.

35. In a sheet-counting apparatus, an accumulator comprising a rotary carrier, a series of sheet-holders carried by said rotary carrier, each of said sheet holders being adapted to receive a collection of sheets, a reciprocating feeder whereby the sheets are delivered to said sheet-holders, said rotary carrier being movable step by step to successively locate the sheet-holders in the path of said reciprocating feeder, counting means including a ratchet wheel adapted to impart a step by step movement to said rotary carrier, an oscillatory pawl adapted to engage said ratchet wheel, said oscillatory pawl being movable in response to each operation of said reciprocating feeder, a rotary shield whereby said pawl is normally retained in a position beyond said ratchet wheel, a second ratchet wheel whereby motion is transmitted to said rotary shield, a second pawl adapted to actuate said second ratchet wheel, a second shield adapted to prevent engagement of said second pawl and ratchet wheel, said second pawl being movable in response to each operation of said feeder, and a controller for said second shield, said controller including an operating member located adjacent to said feeder, said feeder being slotted to receive said operating member so as to permit operation of the feeder independently of said operating member, and said operating member being in the path of the sheet transmitted by said feeder.

36. A bag-turning machine provided with a bag-turning plunger, a gripper into which margins of the bags are forced by said plunger, said plunger being adapted to enter said gripper and said gripper being adapted to hold a collection of bags, and bag-counting means whereby said gripper is shifted in response to a predetermined number of bag-turning operations.

37. In a machine of the character described, a gripper adapted to hold a collection of bags, an opening device whereby said gripper is opened to receive margins of the bags, and a bag-turner cooperating with said opening device to deliver the bags to said gripper.

38. In a machine of the character described, a gripper adapted to hold a collection of bags, an opening device whereby said gripper is opened to receive margins of the bags, and a bag-turner cooperating with said opening device to deliver the bags to said gripper, said bag-turner including a bag-turning plunger whereby margins of the bags are forced into said gripper.

39. In a machine of the character described, a bag-holder provided with a bag-gripper adapted to receive margins of a

collection of bags, an opening device whereby said bag-gripper is opened to receive said margins, and a bag-turner cooperating with said opening device to deliver bags to said bag-holder, said bag-turner including a bag-turning plunger movable over the margins of the bags in said bag-gripper, and said opening device including a pressure member whereby said margins of the bags are displaced and held below the path of said bag-turning plunger.

In testimony that I claim the foregoing I hereunto affix my signature.

DANIEL BELCHER.
